UNITED STATES PATENT OFFICE.

TRUMAN C. SHERWOOD, OF WATSEKA, ILLINOIS.

STORE-FRONT CONSTRUCTION.

1,334,806.

Specification of Letters Patent. Patented Mar. 23, 1920.

Application filed June 15, 1917. Serial No. 174,974.

To all whom it may concern:

Be it known that I, TRUMAN C. SHERWOOD, a citizen of the United States, residing at Watseka, in the county of Iroquois 5 and State of Illinois, have invented new and useful Improvements in Store-Front Constructions, of which the following is a specification.

This invention has reference to display 10 windows for stores or the like, and relates to a casing for such windows designed to ventilate the window for preventing the frosting thereof in cold weather.

In carrying out my invention it is my 15 purpose to produce a frame or casing for the glass of store or other display windows having means associated therewith whereby the inside of the window is constantly ventilated by a stream of cool dry air from 20 the exterior of the window, which is played over the surface of the window and effectively prevents the warm moist-laden air from coming in contact therewith and consequently preventing the formation of frost, 25 since the moisture is not permitted to contact with the cold window.

It is a further object of the invention to produce a window frame or casing having means for directing a circulation of air over 30 the inner surface of the glass and which provides an outlet for the drainage of water either produced by the condensation on the inner side of the window glass or that which flows down upon the inner side of the glass 35 during the washing of the same, and whereby such water or moisture will be prevented from inflicting injury to the wall or the woodwork upon the inner portion of the building adjacent to the window casing.

40 It is a still further object of the invention to produce a window frame or casing that shall be constructed of metal, wherein the glass may be readily attached thereto and which provides means for permitting the 45 circulation of air to flow over the inner face of the said window pane, the said air being directed from both the top and bottom of the frame or casing.

In the drawings:

50 Figure 1 is a perspective view of a portion of the exterior of a store or the like having a window casing thereon constructed in accordance with the present invention.

55 Fig. 2 is an elevation looking toward the inner face of one of the frames or panels constituting the improvement.

Fig. 3 is an approximately central vertical longitudinal sectional view through the same,

Fig. 4 is a transverse sectional view approximately on the line 4—4 of Fig. 3, and

Fig. 5 is a detail sectional view approximately on the line 5—5 of Fig. 3.

In the window opening of the building 1 is arranged a frame or casing constructed 65 in accordance with this invention.

The frame 2 is preferably constructed of metal including channel vertical sides or stiles 3, a channeled top member 4 which is of a greater width than the stiles 3 and 70 which may be connected to the stiles by solder or by any other desired or preferred means. The sill or stool is indicated by the numeral 5 and is of a peculiar construction, the same including side members 6 arranged 75 flush with the outer edges of the stiles 3, an outer face 7 and an inner face 8 spaced from the said outer face 7, so it will be noted that the stool 5 comprises a hollow member. The sides 6 of the stool are of a 80 materially greater width than the thickness of the stiles 3, and extend outwardly of the said stiles at the lower portions of the ends of the stiles, and are from thence continued downwardly in a substantially vertical line. 85 The outer face 7 is connected to the side 6 in any desired or preferred manner, as for instance, the said face may be formed integrally with the sides or the face 7 may be soldered or otherwise secured to the outer 90 edges of the sides, the lower portion of the said face plate 7 being straight, but the upper portion thereof is rounded inwardly to conform with the upper corners of the sides 6, as indicated by the numeral 9, and 95 the said portion 9 is either secured to or forms a part of the inner face 8. The inner face plate 8 is vertically straight, and at a suitable distance from the lower ends of the stiles 3 is provided with an angularly disposed longitudinally extending ledge 10, the said ledge being provided with spaced notches 11, and upon this ledge the lower edge of the window pane 12 rests. It is to 100 be understood that the pane is received in the channels or stiles and in the channel of the top member 4, and by reference to the drawings it will be noted that the opposite faces of the said top 4 above the window pane 12 are provided with preferably 105 oppositely disposed rounded slits, the metal bounded by the said slits being bent out-

110

wardly and angularly to surround the openings 13 thus provided, and to provide directing members or shutters 14. The device being constructed of metal the shutters 14 may be arranged at a desired angle with respect to the frame 2 so that the inner shutters 14 will positively direct air currents downwardly over the inner face of the window pane 12, and the outer shutters 14 may be adjusted to permit of the free entrance of the air at any desired angle with respect to the frame, and the notches 11 in the ledge 10 provide for the entrance of the air from the lower portion of the stool as will hereinafter be more fully set forth, to the inner face of the pane at the lower portion or edge thereof.

The sides 6 of the stool 5 at their lower edges are beveled, as at 15, and the back or inner plate 8 may from its straight surface be bent and continued in the direction of the said inclined edges 15 providing the base 16 of the stool. The outer face of the stool is indicated by the numeral 17 and comprises a rounded plate 18 that has its ends secured to the edges of the sides 6 of the stool. This forms the stool with a hollow compartment which is designated by the numeral 19. The plate 8 is provided with openings 20 communicating with the compartment 19, and the outer plate 7, at its juncture with the base 16 is provided with air inlet openings 21. The inner plate 8, at the portion thereof to which the rounded plate 18 is connected is provided with a series of openings 20, while the outer plate 7 of the stool at its juncture with the base 16 is likewise provided with openings 21. Through these openings 21 the currents of air from the exterior of the building are adapted to pass and from thence through the openings 20 into the compartment 19, and through the notches 11 in the ledge 10 over the inner face of the window pane 12. The

rounded plate 18 has its upper edge flared 45 outwardly away from the stiles 3 and away from the window pane, as indicated by the numeral 22, the said flared portion being arranged a suitable distance above the ledge 10 and provides a directing means for the 50 air currents as well as a means for directing moisture from the window pane to within the compartment 19, the said moisture finding an outlet through the notches 11 in the ledge 10, the openings 20 in the inner 55 plate 8 of the stool and from thence through the openings 21 in the outer plate of the said stool.

From the above description taken in connection with the drawings, it will be noted 60 that the device is comparatively simple in construction, and may be cheaply manufactured. The metallic frame being arranged in the window opening does not interfere with the proper trimming of the 65 window casing and the advantages of the construction will, it is thought, be apparent without further detailed description.

Having thus described the invention, 70 what I claim is:

In a ventilating window construction, a frame having channeled sides and a channeled top receiving a window pane therein, a hollow stool integrally formed with the frame and projecting beyond the lower edge thereof, a transversely disposed notched ledge on one of the walls of the hollow stool supporting the lower edge of the window pane, a compartment inclosing the ledge and having its upper end spaced from contact with the 75 window pane, and said stool having openings which communicate with the compartment and having other openings at the lower portion of the wall thereof opposite that on which the compartment is arranged. 80 65

In testimony whereof I affix my signature.

TRUMAN C. SHERWOOD
